Primary Examiner — Catheri Oliver-Garcia*Assistant Examiner* — Rebekah Caruso(74) *Attorney, Agent, or Firm* — Lathrop & Gage LLP**CLAIM**

The ornamental design for a textured siding panel, as shown and described.

DESCRIPTION

FIG. 1 is a perspective view of a siding panel showing our new design;

FIG. 2 is a front elevation view thereof;

FIG. 3 is a left side elevation view thereof, the right side elevation view being a mirror image;

FIG. 4 is a top plan view thereof; and,

FIG. 5 is a bottom plan view thereof.

The broken away symbols in the drawings indicate that any portion of the article that continues beyond what is shown forms no part of the claimed design.
